Primary Examiner—Alan P. Douglas*Assistant Examiner*—Rosemary K. Tarcza(74) *Attorney, Agent, or Firm*—Foley & Lardner LLP(57) **CLAIM**

I claim the ornamental design for a electrical outlet adapter, as shown and described.

DESCRIPTION

FIG. 1 is a front perspective view of the claimed design; FIG. 2 is a front elevation view of the claimed design; FIG. 3 is a rear elevation view of the claimed design; FIG. 4 is a top view of the claimed design, the bottom view being identical;

FIG. 5 is a left side elevation view of the claimed design; and,

FIG. 6 is a right side elevation view of the claimed design. The ornamental design which is claimed is shown in solid lines in the drawings. The broken lines in the drawings are for illustrative purposes only and form no part of the claimed design.
